Stove and Range Company, Grafton, Wis., a
corporation of Wisconsin

Application November 1, 1935, Serial No. 47,880

8 Claims. (Cl. 126—93)

The invention relates to heaters and more particularly to oil burning heaters.

An object of the invention is to provide an improved oil burning heater which is so constructed as to insure efficient operation.

Another object is to provide a heater having a simple and inexpensive burner mounting.

The invention further consists in the several features hereinafter described and claimed.

This application constitutes a continuation in part of my copending application for Oil burners, Serial No 648,910, filed December 27, 1932.

In the accompanying drawings, illustrating one embodiment of the invention,

Fig. 1 is a front elevation of an oil burning heater constructed in accordance with the invention;

Fig. 2 is a top plan view of the heater parts of a top grille being broken away;

Fig. 3 is a sectional elevation of the heater taken generally along the line 3—3 of Fig. 1;

Fig. 4 is a sectional view taken along the line 4—4 of Fig. 3, a humidifier of the heater being omitted;

Fig. 5 is a fragmentary bottom view of the heater;

Fig. 6 is a detail sectional view taken on the line 6—6 of Fig. 4;

Fig. 7 is another detail sectional view taken on the line 7—7 of Fig. 4;

Fig. 8 is a detail top view of a corner portion of the heater;

Fig. 9 is a detail bottom view of a corner portion of the heater grille;

Fig. 10 is a detail top view of the burner mounting, parts being broken away;

Fig. 11 is a detail sectional view of a burner support taken on the line 11—11 of Fig. 10;

Fig. 12 is a detail inside view of a door construction for the heater, parts being broken away and parts being shown in section, and

Fig. 13 is a detail sectional view taken on the line 13—13 of Fig. 12.

In these drawings, 15 designates a heater casing in which is mounted a liquid fuel burner 16. The casing 15 comprises top and bottom plates 17 and 18, respectively, connected by vertical side walls here shown to be formed by a front panel 19, a rear panel 20, and opposite side panels 21. The top and bottom plates are preferably castings, and the several panels are preferably vitreous enameled sheet metal plates. The bottom plate 18 has supporting legs 22 secured thereto by bolts 22' to form a heater base, the legs being preferably provided with screw feet 23 for leveling.

The top and bottom plates are connected by vertical air heating flues 24 positioned near the side walls of the casing and preferably formed of thin vitreous enameled sheet metal tubes or pipes. The opposite ends of the tubes are tapered or flared and are pressed and cemented onto correspondingly tapered nipples or collars 25 and 26 integrally formed on the top and bottom plates, respectively, the resilient character of the tubes permitting them to conform to the nipples. 5 These plates are further connected by down-draft air tubes or pipes 27 to supply air for combustion. The tubes 27 are similar to the flues and similarly attached to nipples 28 and 29 formed on the respective plates. The upper nipples 28 are 10 open, as seen in Fig. 6, but the lower nipples 29 are closed, as seen in Fig. 7, the air tubes 27 having lateral discharge openings 30 near their lower ends, as seen in Figs. 3 and 7.

The liquid fuel burner is supported on the bottom plate 18 and is preferably of a well-known type embodying a series of perforated cylindrical metal shells or tubes 31 arranged concentrically and carried on a burner base 32. In the present instance the burner base has a central air opening 33 and a series of arcuate air openings 34 thereabout. The innermost shell carries an apertured cover plate 35, and a pair of intermediate shells carry an annular cover plate 36. The bottom wall of the burner base is preferably conically formed so as to slope downwardly toward the part adjacent the central air opening. The burner base is positioned and supported by three spaced legs or ribs 37 projecting upwardly from the heater bottom plate 18 and extending radially of the burner, the ribs having ledges 38 (Fig. 11) on which the burner base rests and having fingers 39 entering the arcuate air openings 34 in the burner base. The ribs 37 also have shouldered ledges 40 which support and position an annular generating and lighting trough 41 below the burner base, the trough having a front filling and igniting extension 42 (Fig. 10) to receive alcohol or other suitable fuel. Preferably, the heater bottom plate 18 has a dished portion 43 below the burner so as 45 to permit a low setting of the burner and thus increase the effective heating capacity of the burner. The dishing of the bottom plate also serves to minimize any tendency to warping. The top plate 17 may be slightly crowned for the same 50 purpose.

The burner base 32 is held firmly down on the supporting ribs 37 by a hook bolt 44, the upper hooked end of which engages a bridge or cross bar 45 integrally formed on the burner base and 55

extending diametrically of the central air opening 33 of the burner base. The hook bolt passes through the heater bottom plate and is secured thereto by a nut 46. The generating trough is 5 confined between the ribs 37 and the burner base.

Liquid fuel, such as kerosene or distillate, is conducted to the burner base by a vertical pipe 47 passing through openings in the generating 10 trough and heater bottom plate. Below the bottom plate the pipe 47 is attached to a T 48 having a plug 49 at its lower end and connected by a tube 50 to a control or metering valve 51 at the front of the bottom plate, the valve being 15 mounted on a bracket 52 secured to the bottom plate. A tube 53 extends from the valve to a constant level valve device 54 mounted at the rear of the heater on a bracket 55 secured to the heater bottom plate. The constant level device 20 is adjustable vertically and determines the maximum height to which oil will rise in the burner base. The liquid fuel is conducted to the constant level device from a supply tank, not shown.

The rear panel 20 has a smoke outlet 56 at its 25 upper portion for connection to a smoke pipe and chimney, not shown, the smoke pipe having the usual damper means. A baffle plate 57 is mounted in the heater casing in front of the rear panel and smoke outlet and has a rearwardly projecting top flange 58 secured by bolts 58' to the top plate 17, as seen in Fig. 3, and a rearwardly projecting bottom flange 59 engaging the rear panel, thus causing the gases of combustion to take a 30 circuitous path to the smoke outlet, as indicated by arrows in Fig. 4. Below the smoke outlet the rear panel has attached thereto a channel shaped supporting bar 60 to detachably carry thereon a humidifying tank 61, the tank having a hooked upper edge 61' engaging the bar.

The bottom plate 18 has a downturned marginal flange 62, and the top plate 19 has an upturned marginal flange 63 with upwardly opening notches 64, both plates preferably having beveled corners. Each of the casing panels has 40 a hooked lower edge 65 engaging the flange 62 of the bottom plate, and has openings 66 near its upper edge to register with the notches 64. Channel members 67 embrace the upturned flanges 63 and upper edges of the panels and are 45 secured thereto by bolts 68 passing through the notches 64 and openings 66.

At their side edges each panel has an angularly extending outwardly hooked portion 69, as best seen in Fig. 8, the edges of adjacent panels 55 being connected by vitreous enameled sheet metal corner strips 70 having hooked or folded edge portions 71 inter-engaging with the hooked portions of the panel. The corner strips 70 are slid lengthwise into position and the interstices between them and the panels are filled with a suitable cement or putty 72. The lower ends of the corner strips are concealed by shoulders or ledges 73 formed on the legs 22.

The front panel of the heater casing is provided with a door opening 74 defined by an inwardly offset flanged portion 15 which forms a door frame against which a door 76 is seated, the door when closed being substantially flush with the outer surface of the panel. The door 70 is supported on vertically aligned pintles 77 and 78 passing through openings in the flanged portion of the panel, the upper pintle 77 being detachable and being of angular shape, as indicated in Fig. 12. The door is held closed by a suitable pivotally mounted handle 79 with an inner

arm 80 which has a cam engagement with the door frame. A resilient sheet metal plate 81 is secured by screws 82 to the inner face of the door against the pivotal axis, and has a cam engagement with the door frame, so that when the door is closed all parts of the door will be firmly seated in the frame to minimize leakage of air into the casing around the door. The door is preferably provided with a pane 83 of heat-resisting glass held in place by clips 84 attached by 10 screws 84'.

The top of the heater casing is preferably surrounded by a detachable grille 85 having a frame comprising corner members 86 connected by sheet metal bars 87 of angular cross-section, the corner members and bars being vitreous enameled and secured together by screws 88. The corner members have inwardly projecting lugs 89 which rest on the beveled corner portions of the heater casing. The frame bars 87 have downturned inner flanges 90 to which the downturned edges of a reticulated grille plate 91 are secured by angle-shaped clamping bars 92 attached to the flanges 90 by screws 93. The grille plate 91 is preferably formed of expanded metal. The same corner members 86 can be used for grilles of different sizes.

In assembling the heater, the air heating flues 24 and down-draft air tubes 27 are pressed and cemented onto the nipples or collars of the top and 30 bottom casing plates 17 and 18 to form a rigid self-supporting structure to which the several side panels and other parts are then attached to complete the assembly.

To start the heater in operation, a small quantity of alcohol is poured in the generating trough 31 and is lighted to heat the burner base to a generating temperature. During the heating, the metering valve 51 is kept closed and the door 76 is kept slightly open. After a few minutes the 40 burner base attains a generating temperature, and the valve 51 is then opened, the door being left open. The flame from the lighted alcohol will then ignite the vapor from the liquid fuel, and when this occurs the door is tightly closed, 45 whereupon the air for combustion is drawn by chimney draft through the down-draft air tubes 27. The air passing down the tubes 27 is preheated by the hot gases of combustion surrounding and heating the tubes, so that the burner base will 50 remain hot to insure complete combustion, notwithstanding variations in air flow incident to changes in draft conditions. Preferably, all the air for combustion is supplied through the down-draft tubes 27, the heater being otherwise devoid 55 of air inlet openings, and the door when closed having a tight fit.

The hot gases of combustion sweep over the air heating flues 24 which surround the burner, and heat the air which passes upwardly through 60 the flues in a straight line path. The heated air rises in the flues with a substantial velocity so as to establish a good circulation of air in the room in which the heater is placed. The flue construction permits a comparatively large 65 air heating surface in a limited space, and the relatively thin walls of the flues insure a rapid heat transfer. In addition to heating the flues, the hot gases of combustion also heat the side walls of the heater casing so as to provide heat 70 by radiation as well as convection.

The heater construction permits the burner unit to be placed close to the bottom wall of the heater casing, so as to provide a large effective heating surface in a limited casing height. The 75

oil piping, except for the short pipe or nipple 47, is placed outside of the casing, so as to avoid heating of the piping and accumulation of carbonized oil in the small diameter piping. After 5 removing the burner shells 31 and bottom plug 49, any accumulated carbon in the pipe 47 can be easily reamed or scraped out.

While the invention is here shown to be embodied in a circulating room heater, it is obvious 10 that it is also applicable to other oil heating devices.

What I claim as new and desire to secure by Letters Patent is:

1. In a heater, the combination of a casing, 15 a liquid fuel burner therein having a vaporizing base and perforated combustion tubes on said base, and an air pipe within said casing extending higher than the burner for supplying preheated combustion air to said burner to prevent cooling of said base notwithstanding variations 20 in air flow to the burner, said air pipe being spaced from said burner.

2. In a heater, the combination of a casing having a top wall, a liquid fuel burner in said 25 casing, and an air pipe extending downwardly from said top wall to be heated by gases of combustion in said casing and having its lower end adjacent the level of the burner and spaced laterally of the burner for supplying preheated 30 combustion air to the burner to avoid cooling of the burner notwithstanding variable draft conditions.

3. In a heater, the combination of a casing having top and bottom walls, a liquid fuel burner 35 in said casing, a downdraft air pipe in said casing to be heated by gases of combustion for supplying preheated air to said burner, said pipe being spaced laterally from said burner and being anchored on said top and bottom walls and having an air inlet at its upper end and an air 40 outlet adjacent its lower end.

4. In a heater, the combination of a casing having top and bottom plates with inwardly extending nipples, a liquid fuel burner in said

casing, and a down-draft air pipe in said casing spaced laterally from the burner and having a pressed connection with said nipples, said pipe having an air inlet at its upper end and having a lateral discharge opening adjacent its lower 5 end for supplying preheated air to said burner.

5. In a heater, the combination of a burner base having a central air opening and a bar across said opening, perforated combustion tubes on said base, a bottom plate having a plurality 10 of projections interengaging with said burner base for supporting and positioning said burner base, and a hold-down rod for said burner base connecting said bottom plate and the bar of said burner base.

6. In a heater, the combination of a bottom 15 plate, supports on said bottom plate, a burner base resting on and positioned by said supports, a generating and lighting trough for said burner base carried by said supports and spaced below 20 said base, and means for securing said burner base to said bottom plate, said burner base confining said generating and lighting trough between said base and said bottom plate.

7. In a heater, the combination of a bottom 25 plate member, a plurality of spaced supports on said member, a burner base resting on and positioned by the upper portions of said supports, a generating and lighting trough member for said burner base carried by said supports and positioned below said burner base and above said 30 bottom plate member, said supports being rigidly connected to one of said members, and means for securing said burner base to said bottom plate.

8. In a heater, the combination of a burner 35 base having a central air opening and a bar across said opening, perforated combustion tubes on said base, a bottom plate, a plurality of spaced projections interengaging with said burner base and supporting said burner base above said bottom plate, and a hold-down rod for said burner base connecting said bottom plate and the bar of said burner base.

JOHN JUNGERS.
